(57) **CLAIM**

The ornamental design for an integrated multi-channel ABS rear axle brake module, as shown and described.

DESCRIPTION

FIG. 1 is a top right front perspective view of a first embodiment of the integrated multi-channel ABS rear axle brake module showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof;

FIG. 7 is a top plan view thereof;

FIG. 8 is a top right front perspective view of a second embodiment of the integrated multi-channel ABS rear axle brake module showing our new design;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.

The broken lines showing of openings depicts environment and forms no part of the claim.
